UNITED STATES PATENT OFFICE.

HANS CHRISTIAN FRIEDERICH LASE, OF BANCROFT, NEBRASKA, ASSIGNOR OF ONE-HALF TO KARL J. KOLLMORGAN, OF BANCROFT, NEBRASKA.

POST PULLER.

Application filed January 22, 1925. Serial No. 4,075.

To all whom it may concern:

Be it known that I, HANS CHRISTIAN FRIEDERICH LASE, a citizen of the United States, residing at Bancroft, in the county of Cuming and State of Nebraska, have invented certain new and useful Improvements in Post Pullers, of which the following is a specification, reference being had to the accompanying drawings.

This invention relates to certain improvements in post pullers and it is an object of the invention to provide a device of this kind particularly adapted for use for the removal of fence posts.

Another object of the invention is to provide a device of this general character constructed in a manner whereby a post is pulled substantially straight out of the ground.

The invention consists in the details of construction and in the combination and arrangement of the several parts of my improved post puller whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating a puller constructed in accordance with an embodiment of my invention and in initial applied position;

Figure 2 is a view similar to Figure 1 but showing the lifting beam in a second position with the post partly withdrawn;

Figure 3 is also a view similar to Figure 1 showing the lifting beam in the position when the post is substantially entirely withdrawn;

Figure 4 is a view in top plan of my improved device as herein disclosed;

Figure 5 is a sectional view taken substantially on the line 5—5 of Figure 4.

As disclosed in the accompanying drawings, 1 denotes an axle of requisite dimensions and which is supported by the ground engaging wheels 2. B denotes an elongated beam provided at one end with a goose neck 3, said beam B immediately adjacent to the

neck 3 being pivotally connected to the central portion of the axle 1 by the U-bolts 4 bridging or looping the axle 1 from below and having their extremities operatively engaged from above, as at 5, with the beam B. 60

The applied beam B has the goose neck or curved end portion 3 disposed in a direction away from the axle 1, said neck or portion 3 preferably being arcuate and of a length substantially equal to eighty degrees of a circle and of substantially the same radius as a wheel 2 so that when the beam B is vertically disposed, as in Figure 1, said portion 3 will have contact with the ground whereby said beam B will be readily maintained in such position.

The beam B and the neck or portion 3, as herein disclosed, are angular in cross section but the outer or free extremity of the neck or portion 3 is flattened to provide a 75 plate 6 coplanar with the beam B, the outer edge a of said plate being straight and arranged on a slight incline diverging inwardly of the beam B.

The plate 6 adjacent the opposite ends of the straight edge a is provided with openings 7 through which is adapted to be selectively disposed a bolt 8. Secured to the applied bolt 8 at opposite sides of the plate 6 are extremities of the chains 9 of desired 85 length, one of said chains being provided at its free end with a hook member 10 to engage with a link of the second chain when it is desired to anchor or connect the plate 6 to its work, such as a fence post P. 90

The beam B has secured to opposite sides thereof, as at 11, the extremities of the brace members 12, the opposite end portions of said members being attached, as at 14, to the axle 1 at points in close proximity to the 95 wheels 2. The brace members 12 adjacent their connection with the axle 1 have secured thereto, as at 15, the brace members 16 which are also fixed, as at 17, to the outer extremity of the neck or portion 3. 100

The end of the beam B remote from the neck or portion 3 has affixed thereto a clevis 18 to which is attached an extremity of a flexible member 19 herein disclosed as a chain. 105

In practice when it is desired to pull a post P my improved device is positioned with the beam B vertically disposed and the plate 6 immediately adjacent to the post at the ground line thereof as illustrated in 110

Figure 1. After the chains 9 have been suitably engaged around the post P pull is imposed upon the upper end portion of the beam B resulting in upward swinging movement of the neck or portion 3 carrying the post P therewith as illustrated in Figure 2, and when the beam B has reached substantially a horizontal position the post P is substantially entirely removed from the ground as illustrated in Figure 3. As the plate 6 moves upwardly the wheels 2 will travel inwardly toward the post P whereby it is assured that the removal of the post P will be in substantially a straight line where-
10 by the pulling operation may be accom-
15 plished with a pronounced ease and facility.

The chain 19 is adapted to be coupled to a wagon or other vehicle to effect the requisite pull upon the beam B but I do not wish to be
20 understood as limiting myself to this par-
25 ticular operating power.

From the foregoing description it is thought to be obvious that a post puller constructed in accordance with my invention
25 is particularly well adapted for use by rea-
son of the convenience and facility with
which it may be assembled and operated,
and it will also be obvious that my inven-
30 tion is susceptible of some change and modi-
fication without departing from the prin-
ciples and spirit thereof and for this reason

I do not wish to be understood as limiting myself to the precise arrangement and formation of the several parts herein shown in carrying out my invention in practice except 35 as hereinafter claimed.

I claim:—

A post puller comprising, in combination, an axle, ground engaging means supporting said axle, a beam provided at one end with an upstanding arcuate extension, means for operatively connecting said beam with the axle to permit said beam to have swinging movement in a vertical direction, such connection between the beam and axle being at 40 a point in close proximity to the arcuate extension, said arcuate portion being disposed on a radius to contact with the ground when the beam is vertically disposed to maintain the beam in such position, the 45 outer end portion of the beam being flattened to provide a plate coplanar with the beam, the outer edge of said plate being straight and arranged on a slight incline converging inwardly toward the beam, and 50 work engaging means secured to the plate adjacent to the inner or lower end of the inclined edge of the plate.

In testimony whereof I hereunto affix my signature.

HANS CHRISTIAN FRIEDERICH LASE.
